Primary Examiner — Karen E Eldridge Powers

(57) **CLAIM**

I claim the ornamental design for a cap with integrated fan, as shown and described.

DESCRIPTION

FIG. 1 is a side elevation view of the cap with integrated fan.
 FIG. 2 is a front elevation view of the claimed design.
 FIG. 3 is a top plan view of the claimed design.
 FIG. 4 is a bottom plan view of the claimed design; and,
 FIG. 5 is a bottom, perspective view of the claimed design.

1 Claim, 3 Drawing Sheets**FIG. 1**

FIG. 2

FIG. 3

FIG. 4

FIG. 5
